UNITED STATES PATENT OFFICE

HARVEY H. ESLINGER, OF HECKTOWN, PENNSYLVANIA, ASSIGNOR TO ESLINGER MOTORS COMPANY, A CORPORATION OF DELAWARE

VALVE MECHANISM FOR INTERNAL-COMBUSTION ENGINES

Application filed July 2, 1924, Serial No. 723,630. Renewed May 14, 1930.

The invention relates to valve mechanism for four cycle engines in which use is made of a single reciprocating piston valve.

The principal objects of the present invention are, first, to provide a simple, reliable and efficient construction; second, to provide free and easy passage for both the intake and exhaust; third, to prevent overheating of the valve and valve rod; and fourth, to provide for sufficient lubrication of the valve.

Other objects of the invention will appear from the following description and the invention will be claimed at the end hereof after having been first described in connection with the embodiment of it chosen for illustration in the accompanying drawings in which

Figure 1 is a schematic and diagrammatic sectional view of mechanism embodying features of the invention, and

Fig. 2 is a sectional plan view illustrating a detail of construction.

In the drawings 1 is a valve cylinder open or having an opening through its outer end 2 to exhaust 3, and this valve cylinder is provided at its inner end with a valve receiving chamber 4 arranged out of the path of the exhaust. Through the bottom wall 5 of this chamber 4 is arranged a valve rod opening 6. The cylinder 1 above the chamber 4 and at the top of the chamber 4 is provided with an engine cylinder port 7, and between the top and bottom of the chamber 4 there is an intake port 8. 9 is a piston valve reciprocable in the cylinder 1 and adapted for retraction into the chamber 4 to uncover the engine cylinder port 7 and permit exhaust to pass over the top of the valve 9. In this position the valve can be satisfactorily lubricated because it is not unduly heated by the exhaust which passes and rises above it. Lubricant may be supplied through the feed pipe 10 and delivered to the duct 11 opening radially into the valve rod 12 and extending axially through the same and then radially as at 13 and 14 to the cylindrical surface of the valve. The piston valve is also adapted for projection out of the chamber 4 to uncover the inlet port 8 and the engine cylinder port 7. 15 is a packing ring of metal ar-

ranged in a peripheral groove in the valve piston 9 and when it exceeds in depth the distance between the top and bottom walls of the engine cylinder port 7 it spans the opening and consequently works smoothly and efficiently. Between the packing ring 15 and the wall of the groove in which it is arranged the lubricant is introduced through the duct 14. The bottom surface of the piston valve 9 is shown at 16 as upwardly beveled in proximity with the port 7 which promotes clearance and promptness in uncovering the port 7 for the introduction of charges. It will be observed that the valve rod 12 and the bearing or opening in the wall 5 through which it works are not exposed to the direct heat of the exhaust and are therefore permitted to remain comparatively cool. The shafts 17 and 18 are driven in such relation that the shaft 17 makes two revolutions for each revolution of the shaft 18. On the shaft 18 is a cam 19, the high part 20 of which is substantially circular so that the valve 9 is held or caused to dwell in its uppermost position to facilitate the ready intake of the charge. The valve rod 12 is caused to follow the cam by the action of the spring 21, and the valve rod is shown as provided with a forked end in which there is a cam roller 22. The fork at the end of the rod 12 is one way of keeping the valve 9 from rotation which if permitted might displace not only the part 16 but also disarrange the location of the split in the metal packing ring 15. In Fig. 2 the location of the split γ in the ring is clearly shown. Of course the described valve cylinder may be provided in the same piece or casting as the engine cylinder 31, or the valve cylinder, or more accurately, a series of valve cylinders may be provided in a separate casting secured to the engine casting 31, and the latter is the construction illustrated in the drawings.

The mode of operation may be described as follows:

As shown in the drawings the valve 9 and its gear including the cam 19 are in position for exhaust. It is important that the exhaust passes over the top of the valve 9 and that the valve 9 is retracted into the chamber 4 be-

cause neither the valve nor its rod and rod bearing is unduly heated and because lubrication can be advantageously effected. Furthermore the exhaust is unobstructed. The operation of the high part 20 of the cam projects the valve from the chamber 4 above the engine cylinder port 7 in which position it dwells, thus affording a free passage for the intake 8, and when the valve rises it is properly lubricated and tends to clean or sweep the valve cylinder in the direction of the exhaust.

The portion 21 of the cam corresponds to exhaust and the portion 22 corresponds to the power stroke. The cam consists of concentric parts of different radii adapted to produce the described valve action. The upper face of the piston valve is beveled for a purpose like the under face 16.

In the claims the reference to a piston valve that is solid is intended to mean a piston valve devoid of ports for fuel or exhaust products and not made up of relatively movable sleeves.

It will be obvious to those skilled in the art to which the invention relates that modifications may be made in details of construction and arrangement without departing from the spirit of the invention which is not limited as to such matters or otherwise than as the prior art and the appended claims may require.

Upon reference to the drawing it is evident that the valve rod 12 is rigidly connected with the valve and is guided by two bearings 5 and 30, spaced apart, and that the bearing 30 is quite close to the cam. The support and rigidity of this construction keeps the valve in alignment and assists in resisting the force of the explosion against the cylindrical face of the wall of the valve.

I claim:

1. Valve mechanism for internal combustion engines including a valve cylinder having an oil passage through its wall and having at low level an intake and at intermediate level an engine port and at high level an exhaust and having at its inner end a valve chamber extending below the engine port, a solid piston valve having an oil duct extending radially through it and axially and radially through its stem and constituting the sole means for controlling said port and intake and exhaust and having a single packing ring adapted in low position of the valve to enter said chamber and seal the inlet and to uncover the engine port to exhaust, and said ring adapted in high position of the valve to seal the exhaust and to uncover the engine port and intake, and said ring in intermediate position of the valve adapted to span and cover the engine port and to receive and confine the explosion, a guide for the stem of the valve provided with an oil passage, and spring pressed cam means for reciprocating said valve with a dwell in its movement at each of said positions, said spring pressed cam means confined below said valve and protected by it from the heat of the exhaust and provision for preventing rotation of the valve and insuring oil feed to the oil passage.

HARVEY H. ESLINGER.

tions, said spring pressed cam means confined below said valve and protected by it from the heat of the exhaust and provisions for preventing rotation of the valve and insuring oil feed at low position of the valve.

2. Valve mechanism for internal combustion engines including a valve cylinder having at low level an intake and at intermediate level an engine port and at high level an exhaust and having at its inner end a valve chamber below the engine port and a radially arranged lubricant feed opening, a piston valve having a split packing ring and a radially arranged lubricant duct extending to the packing ring and having a rod provided with an axial duct and with a radial duct arranged for communication with said lubricant opening in low position of the valve, the split in the packing ring being disposed out of alignment with said ports, the piston valve constituting the sole means for controlling said port and intake and exhaust and adapted in low position to present its upper face below the engine port to seal the inlet and uncover the engine port to exhaust, a cam and a spring arranged below the chamber for actuating the valve rod, and means for preventing rotation of the valve rod to insure oil feed in the low position of the valve.

3. Valve mechanism for internal combustion engines including a valve cylinder having at low level an intake and an intermediate level an engine port and at high level an exhaust and having at its inner end a valve chamber extending below the engine port, a solid piston valve having an oil duct extending radially through it and axially and radially through its stem and constituting the sole means for controlling said port and intake and exhaust and having a single packing ring adapted in low position of the valve to enter said chamber and seal the inlet and to uncover the engine port to exhaust, and said ring adapted in high position of the valve to seal the exhaust and to uncover the engine port and intake, and said ring in intermediate position of the valve adapted to span and cover the engine port and to receive and confine the explosion, a guide for the stem of the valve provided with an oil passage, and spring pressed cam means for reciprocating said valve with a dwell in its movement at each of said positions, said spring pressed cam means confined below said valve and protected by it from the heat of the exhaust and provision for preventing rotation of the valve and insuring oil feed to the oil passage.
